UNITED STATES PATENT OFFICE.

OSCAR M. LEICH, OF GENOA, ILLINOIS, ASSIGNOR TO CRACRAFT, LEICH ELECTRIC COMPANY, OF GENOA, ILLINOIS.

CIRCUIT-CONTROLLING DEVICE.

1,115,446.

Specification of Letters Patent. Patented Oct. 27, 1914.

Application filed February 20, 1913. Serial No. 749,618.

To all whom it may concern:

Be it known that I, OSCAR M. LEICH, a citizen of the United States, residing at Genoa, in the county of Dekalb and State of Illinois, have invented a certain new and useful Improvement in Circuit-Controlling Devices, of which the following is a full, clear, concise, and exact description, reference being had to the accompanying drawings, forming a part of this specification.

My invention relates to circuit controlling devices and provides means for the purpose of transmitting a prolonged impulse over a circuit.

More particularly my invention is applied to desk or portable telephone stands, the switching means being under the control of the switchhook to transmit a prolonged impulse preferably whenever the hook is moved either up or down.

The general nature of the switching devices is such that after the hook has come to rest the impulse ceases, the devices being of such a character to prolong this impulse beyond the time that would ordinarily be given to it with its length dependent solely upon the time required to move the switchhook lever from one limiting position to the other.

I will describe one form which my invention may take by referring to the accompanying drawings, in which—

Figure 1 is a sectional view of a desk telephone constructed in accordance with my invention; Fig. 2 is a detail of construction; Fig. 3 is a bottom view of the stand, and Figs. 4 and 5 are alternate views of the switching devices.

Referring more particularly to Fig. 1, I show a switchhook lever 1 adapted to control a plunger 2, which plunger is normally pressed upwardly by a spring 3 so that this plunger 2 follows the movement of the switchhook lever 1. The movements of this switchhook lever of course are suitably under the control of the subscriber through the agency of the head telephone or receiver 4. The plunger through the agency of the conical portion 5 engages a roller 6 mounted upon a spring 7, thus to change the condition of certain switching springs as the plunger is moved up and down. The arrangement of these springs and their operation, however, does not form part of my present invention.

My invention herein is particularly concerned with the control of the circuit through springs 8, 9, 10 and 11, the control of which springs is also suitably effected by the plunger 2. These springs are suitably mounted on a plate 12 held in place by means of the screws 13 upon the radial arms 14 and 15, which radial arms are secured together with the standard 16 and base 17. These springs 8, 9, 10 and 11 are so arranged that springs 10 and 11 are in electrical contact, being connected together as more clearly shown in Fig. 5, but these two springs are insulated from the springs 8 and 9, which springs 8 and 9 are also insulated from each other by means of the pieces of insulation 18, a suitable distance piece 19 then being interposed between these springs and insulation and the arm 12, suitable screws 20 holding these beforementioned parts together. These springs 8, 9, 10 and 11 are adapted to control a signal sending circuit and for this reason are designed to transmit an impulse whenever the switchhook lever 1 moves from one limiting position to the other. It is of course necessary therefore that these springs be so arranged that a contact is made as the switchhook lever 1 moves, which contact is broken sometime after the lever reaches its limiting position. It is necessary to have this impulse of a prolonged character because the sudden impulse due to momentary contact frequently does not overcome the self-induction of the circuit and fails for other reasons, and to this end suitable delaying means presently to be described, of novel character, are provided to prolong this impulse beyond the time which would be given to it were its time duration dependent merely upon the movement of the switchhook. In a specific form herein shown therefore, it will be seen that the switchhook lever 1 in one position controls the springs 7 to arrange the talking circuit for conversation and in the other position opens the talking circuit and this switchhook lever at the same time as it moves downwardly causes springs 9 and 10 to engage to close a circuit, and on its upward movement causes springs 8 and 11 to engage to close a circuit. This circuit between these springs however is always open, shortly after being made so that it is not of the permanent character, but is merely a passing circuit closure, which passing cir-

cuit closure provides a prolonged impulse. The plunger 2 has a portion 21 of restricted diameter adapted to engage the forked arm of a lever 22, which lever is pivotally mounted to a depending arm 23 of the plate 12 through the agency of the shaft 24. As the plunger 2 moves up and down the lever 22 is oscillated as is readily apparent. This lever 22 has a downwardly extending arm 25 which carries a trigger 26, shown more in detail in Fig. 2. This trigger has apertures 27 so that by means of a shaft 28 it is mounted upon the arm 25 as stated. This trigger 26 is preferably made of one piece and consists of a substantially U-shaped framework 29 having an arm 30 bent away therefrom and then parallel thereto, and then having a further arm 31 similarly bent. The arms 30 and 31 are respectively provided with apertures 32, 32 to which coiled springs 33 are attached, and the opposite extremities of these coiled springs are mounted upon arms 23, 23 which extend downwardly from the plate 12 and which also carry the lever 22.

The trigger has a piece of insulation 34 preferably cylindrical extending from the arm 31 and this is held in place by means of a screw 35 extending preferably through both legs of the U-shaped portion 29. This insulating element 34 is designed to engage the springs 10 or 11 as the case may be to press the same into engagement with the springs 8 or 9. The lever 22 has a bent portion 36 against which the trigger rests in one of its limiting positions. In the other limiting position the inclined surface 37 of the trigger rests against the surface 38 (Fig. 5) of the lever 22.

It will be seen more clearly from Fig. 5, which shows the elements in a more or less intermediate position that the spring 33 is only in line with the pivotal mounting of the trigger 26 during such intermediate position and that these springs 33 will reverse the position of the element 26 the minute this element has slightly passed the neutral point. The springs serve the purpose of placing the roller 34 in an intermediate position such as shown in Fig. 4 after an actuation of the springs. As the lever is in its uppermost position the elements all have the position shown in Fig. 4. Should the lever be moved downwardly, then the plunger 2 of Fig. 5 would travel just a trifle lower than the position shown in Fig. 5, and will force the parts into the position shown in Fig. 1, with the surfaces 37 and 38 in engagement. In this position it will be seen that the springs have again restored the trigger to such a position that the roller 34 holds the springs 10 and 11 in an intermediate position, not contacting with either the spring 8 or the spring 9. This it is thought will illustrate the manner of operation. The

trigger 26 by reason of the spring action prolongs the contact between either of the springs 10 and 11 and that particular spring 8 or 9 with which said springs 10 and 11 may be in engagement.

From what has been described it is thought the invention will be clear as will also the fact that many modifications may be made thereof without departing from its spirit, as the specific device illustrated herein is for illustrative purposes merely, and

What I therefore claim as new and desire to secure by Letters Patent is:

1. In a device of the character described the combination with a pair of springs electrically connected together, and having bent diverging ends, additional springs one adapted for association with each of the springs aforesaid, an element adapted for interposition between the diverging ends of the aforesaid springs adapted to move one or the other of said springs, a lever for moving said elements, and resilient means interposed between said lever and said elements.

2. In a device of the character described the combination with a pair of springs electrically connected together, and having bent diverging ends, additional springs one adapted for association with each of the springs aforesaid, an element adapted for interposition between the diverging ends of the aforesaid springs adapted to move one or the other of said springs, a lever for moving said element, and a spring interposed between said lever and said element.

3. In a device of the character described the combination with a pair of springs electrically connected together, and having bent diverging ends, additional springs one adapted for association with each of the springs aforesaid, a trigger adapted for interposition between the diverging ends of the aforesaid springs adapted to move one or the other of said springs, a lever for moving said trigger, and a spring interposed between said lever and said trigger.

4. In a device of the character described the combination with a pair of springs electrically connected together, and having bent diverging ends, additional springs one adapted for association with each of the springs aforesaid, a trigger adapted for interposition between the diverging ends of the aforesaid springs adapted to move one or the other of said springs, a lever for moving said trigger, and a spring interposed between said lever and said trigger, said trigger having means forming angularly disposed surfaces adapted to engage the lever to define the limits of the movement of said trigger.

5. In a device of the character described the combination with a switch spring, a second switch spring adapted for periodic engagement therewith, and means for control-

ling the periodic engagement of said springs, said means including a lever, a trigger thereon, and yielding means interposed between said trigger and lever.

- 5 6. In a device of the character described the combination with a switch spring, a second switch spring adapted for periodic engagement therewith, and means for controlling the periodic engagement of said springs,
10 said means including a lever, a trigger thereon, and yielding means interposed between

said trigger and lever to actuate said trigger when at its critical position to thereby cause engagement of said springs during movement only of said controlling means. 15

In witness whereof, I hereunto subscribe my name this 5th day of February, A. D. 1913.

OSCAR M. LEICH.
